UNITED STATES PATENT OFFICE

2,441,954

PULSE MODULATION COMMUNICATION SYSTEMS

Prafulla Kumar Chatterjea and James Kinloch Beney, London, England, assigns to Standard Telephones and Cables Limited, London, England, a British company

Application May 21, 1945, Serial No. 594,871
In Great Britain December 20, 1944

5 Claims. (Cl. 179—171.5)

1

The present invention relates to arrangements for generating rectangular electrical pulses of adjustable duration.

In the specification of co-pending British application No. 5940/44 there is described an arrangement involving the use of a gas-filled triode or soft valve for generating pulses of adjustable duration. The present specification describes an alternative arrangement employing only ordinary hard valves. The principal feature of the invention consists in an arrangement of two ordinary triode valves coupled together in such a manner that they exhibit properties very similar to the firing and extinguishing characteristics of the well-known gas-filled triode.

The invention provides an arrangement for generating periodic electrical waves comprising two thermionic valves each having at least a cathode, a control grid and an anode, a source of anode current for the said valves, means for coupling the anode of the first valve to the control grid of the second valve, means for applying saw-tooth waves to the control grid of the first valve, means for feeding back the output variations of the second valve in positive phase to the input of the first valve, and means for deriving periodic waves from either of the said anodes.

According to a minor modification, the two valves are replaced by a double triode having a single cathode common to both triode portions.

The invention will be described with reference to the accompanying drawings, in which—

Fig. 1 shows a schematic circuit diagram of an arrangement according to the invention;

Fig. 2 shows a valve characteristic; and

Fig. 3 shows wave form curves employed to explain the action of Fig. 1.

Referring to Fig. 1, which shows a schematic circuit diagram of one embodiment of the invention, a double triode vacuum valve 1 has a cathode 2 common to both sections. The two separate control grids are designated 3 and 4, and the corresponding separate anodes are 5 and 6, respectively. Alternatively, two similar single triode valves in separate envelopes, with their cathodes connected together, could be used instead if preferred. The cathode 2 is connected to the grounded negative terminal 7 of the high tension source through a load resistance 8. The two anodes 5 and 6 are connected to the positive high tension terminal 9 through individual anode resistances 10 and 11, and a common resistance 12, a bypass condenser 13 being provided.

An arrangement for biasing the control grids 3 and 4 either positively or negatively comprises

2

two equal resistances 14 and 15 connected in series across a direct current source intended to be connected to the terminals 16 and 17. The junction point of these resistances is connected to ground, and the terminals 16 and 17 are further shunted by two potentiometers 18 and 19. The control grids 3 and 4 are respectively connected to the movable contacts of potentiometers 18 and 19 through resistances 20 and 21, the usual by-pass condensers 22 and 23 being provided.

The anode 5 is connected to the control grid 4 by a blocking condenser 24. A saw-tooth wave generator (not shown) of any suitable type is intended to be connected to the input terminals 25 and 26, and supplies waves through a resistance 27 to the control grid 3. This resistance forms a reducing potentiometer with the resistance 20, so that a suitable fraction of the saw-tooth voltage is applied to the control grid 3. The resistance 27 is shunted by a condenser 28, which compensates in known manner for the frequency distortion introduced by the stray capacity shunting the resistance 20.

The anode 6 is connected to the output terminal 29 through a condenser 30. A resistance 31 is provided to shunt the terminals 7 and 29, and forms with the condenser 30 a pulse differentiating circuit. Modulating voltages may be applied to the control grid 3 from the input terminal 32 through the blocking condenser 33 and resistance 34; or alternatively, they may be applied to the other control grid 4 from the input terminal 35 through the blocking condenser 36 and resistance 37.

The manner in which the circuit is believed to operate will be explained with reference to the characteristic curve of Fig. 2, and to wave form diagrams of Fig. 3 which are based on curves obtained experimentally with a circuit in which the significant elements had the values quoted in the table below:

Element	Resistance, Ohms	Element	Capacity, Mfd.
45			
10.....	5,000	13.....	2
11.....	5,000	22.....	0.1
12.....	5,000	23.....	0.1
20.....	10,000	24.....	0.1
21.....	20,000	28.....	50×10^{-6}
27.....	0.25×10^6	33.....	0.1
34.....	0.5×10^6	36.....	0.1
50 37.....	20,000		

The two triode portions of the valve 1 are supposed to be similar, a typical characteristic curve for either being shown in Fig. 2. This shows the relation between the anode current I_a and the

control grid voltage V_g with respect to the cathode. The grid bias of the left hand portion of the valve is adjusted by means of the potentiometer 18 to a value such that when a driving voltage is applied at the terminal 25, the anode current I_a varies between a value given by the point 38 on the lower band, a little above the cut-off point, and a value given by a point 39 somewhere below the saturation point of the valve, so that the working point varies over the portion of the characteristic curve between the points 38 and 39, and the grid voltage swings between the corresponding values OM and ON. The grid bias of the right hand half of the valve is adjusted by the potentiometer 19 to a relatively large positive value OQ, when the left hand half is in the condition represented by the point 38. This value OQ should correspond to a point on the upper bend of the characteristic curve, or it may be well above the saturation voltage for the valve. Since both anode currents flow through the resistance 8, both of these currents affect the potentials of both grids with respect to the common cathode, and the bias adjustments mentioned above should be such as to produce the desired values OM and OQ simultaneously.

The total grid voltage swing of the right-hand half of the valve is PQ, which is greater than the corresponding swing MN for the other half of the valve. The voltage corresponding to P should be well beyond the cut-off voltage. Thus the anode current of the right-hand half of the valve alternates between a relatively large or saturated valve, and zero. These points will be made clearer with reference to the wave-form curves of Fig. 3. Curve A shows the saw-tooth wave voltage applied between the terminals 25 and 26 of Fig. 1 with respect to time, the dotted line 40 representing zero voltage. Curve B represents the corresponding voltage variations of the anode 5, the dotted line 41 representing the voltage at the junction point of resistances 10 and 11. Curve C represents the voltage variations of the anode 6, the dotted line 41 representing the same as before. Curve D shows the variations of the cathode voltage, ground potential being represented by the dotted line 42.

At the termination of the fly-back strokes of the saw-tooth wave, the anode current of the left-hand half of the valve is small, so that the potential of the anode 5 will be a little below the voltage of the dotted line 41, as represented by the points 43. The anode current in the right-hand half of the valve is a maximum and the corresponding anode voltage is a minimum as indicated by the points 44. As the saw-tooth voltage increases from zero, the anode current of the left-hand half increases and the voltage of the corresponding anode falls. This change will, however, be small due to the action of the cathode resistance 8. This fall of voltage is communicated through the condenser 24 to the control grid 4, and nothing further happens until an appreciable decrease in the anode current of the right-hand half of the valve occurs. This decrease acting in the resistance 8 increases the potential of the control grid 3 with respect to the cathode, and so accelerates the fall of voltage of the anode 5, and this change is fed round again so that in effect the right-hand half proceeds rapidly beyond the cut-off, the voltage of the anode suddenly rising to the maximum represented by the points 45. The sudden decrease in cathode potential produces a sudden increase in the left-hand anode current and a corresponding

fall in the voltage of the anode 5 at the points 46. With the continued rise in the saw-tooth voltage, the voltage of the anode falls slowly to the points 47, when the fly-back stroke occurs, and returns to the voltage of the anode 5 quickly to the starting points 43. At some point during the fly-back stroke the right-hand half of the valve is suddenly returned to the saturation points 44, the feedback through the cathode resistance 8 acting to accelerate the change.

The corresponding changes in the cathode voltage are shown in the curve D. Thus during the periods of the anode pulses the cathode voltage is relatively large and rises slightly as the left-hand anode current rises. With the cutting off of the right-hand half, there is a sudden fall in the cathode voltage followed by an immediate small rise and then a slower rise corresponding to the slow change in anode voltage, between the points 46 and 47. When the fly-back stroke occurs, there is a relatively rapid fall in cathode voltage followed by a sudden rise at the moment of saturation of the right-hand portion of the valve.

It will be seen that the voltage pulses (curve C) which can be obtained from the anode 6 are very nearly rectangular. The pulses (curve B) could, if desired, be obtained from the anode 5, but they are of inferior form due to the fact that the left-hand half of the valve is only operated over part of its characteristic curve.

The timing of the leading edges of the pulses from the anode 6 is fixed by the fly-back strokes, but the timing of the trailing edges can be adjusted by adjustment of either of the potentiometers 18 or 19. Reducing the negative bias OM or the positive bias OQ makes the trailing edges occur earlier, and increasing either bias makes them occur later. Thus by applying modulating signals at terminal 32 or at terminal 35, the trailing edges of the pulses from the anode 6 may be time modulated. Thus time-duration modulated pulses may be obtained direct from the anode 6, or pairs of short marking pulses one of which in each pair in time-phase modulated may be obtained from terminal 29 after differentiation by the elements 30 and 31.

It will be appreciated that the double triode 1 with its associated circuits operates practically in the same way as a grid controlled gas filled triode of which the cathode, control grid and anode are represented by the elements 2, 3 and 6 respectively.

The arrangement of Fig. 1 can be regarded as a two-stage amplifier in which the cathode resistance 8 acts to feed back the output variations to the input in positive phase. It also acts to introduce local negative feedback in each stage separately. It will be understood that the desired results according to the invention can be obtained by introducing the positive feedback in other ways.

The numerical values given above for illustration are of course not the only values which can be used, and do not indicate any essential relations between the various elements; for example, the resistances 10, 11 and 12 are not necessarily equal.

What is claimed is:

1. An arrangement for generating variable duration pulses in accordance with applied signal energy comprising, a double valve having two sections each including an anode and a control grid, and a cathode common to both sections, means for applying a direct current potential between

the anodes of said sections and said cathode, means for coupling the anode of the first section to the control grid of the second section, means for feeding back the output variations of the second section in positive phase to the input of the first section, means for biasing the first section to operate from above cut-off to below the upper knee of its characteristic curve, means for biasing the second section to operate from below cut-off to at least the upper knee of its characteristic curve, means for applying control waves to the control grid of the first section, means for applying the signal energy to one of said control grids, and means for deriving variable duration pulses from one of said anodes.

2. An arrangement according to claim 1 wherein the means for applying control waves to the grid of the first section includes means for producing and applying sawtooth waves.

3. An arrangement according to claim 1 further including means for differentiating the variable duration pulses to produce variable time displaced pulses.

4. An arrangement according to claim 1 further including means for adjusting the durations of the derived pulses.

5. An arrangement according to claim 1 further including means for adjusting the durations of the derived pulses including means for adjusting the bias of one of said control grids.
